UNITED STATES PATENT OFFICE.

ALFRED T. KELLIHER, OF BETHEL, MAINE.

ELEVATED CARRIER.

SPECIFICATION forming part of Letters Patent No. 487,485, dated December 6, 1892.

Application filed October 13, 1891. Serial No. 408,564. (No model.)

To all whom it may concern:

Be it known that I, ALFRED T. KELLIHER, a citizen of the United States, residing at Bethel, in the county of Oxford and State of 5 Maine, have invented certain new and useful Improvements in Elevated Carriers, of which the following is a specification.

My invention relates to elevated carriers for conveying logs, lumber, stone, coal, cane, 10 and other bulky materials, and is particularly useful for conveying logs through the forest from the stump to the sawmill.

The object of my invention is to provide an elevated carrier which can be rapidly erected 15 and strong enough to support heavy loads and which can be constructed at small cost. To this end I preferably employ, in combination, a suitable supporting framework of peculiar construction, hereinafter to be described, a track-beam, and a track-rail consisting of a round rod or pipe supported upon bearers having one end fashioned to grasp the track rod or rail and the other adapted to pass into or through the track-beam. 20 Where forest trees are so situated that they can be utilized as supports for the track-beam, I may use them for the uprights and bolt or otherwise fasten thereto the longitudinal track-beam, to which the track-rail is secured. In some instances it may be found 25 expedient to secure this track-rail upon the outer and upper corner of the longitudinal beam; but I prefer to support the track-rail, as before stated, upon bearers inserted in the 30 face of the longitudinal beam.

In the accompanying drawings, Figure 1 is a side elevation of my improved log-carrier, showing a section thereof supported by two trees. Fig. 2 is a cross-section thereof, showing a bucket for carrying coal, ore, &c., suspended from the truck. Fig. 3 is a perspective view of a section of the carrier, showing the track supported by a specially-built frame consisting of parallel uprights with 45 transverse cross-beams supported upon their outer ends and the track-beams suspended therefrom by hangers. Fig. 4 is a perspective view showing a track-support of modified construction. Fig. 5 is a similar view 50 showing the preferred construction of such modified form. Fig. 6 is a cross-sectional

view thereof, and Fig. 7 is an enlarged detail view of one of the track-bearers.

In the drawings, 8 represents the bodies of trees, which may be utilized wherever 55 convenient for the vertical supports of the carrier-frame. 9 represents a beam, which is secured in longitudinal position at a suitable height above the ground to the bodies of said trees. As shown in Figs. 1 and 2, these 60 beams are square timbers secured by the bolts 10, passed through the bodies of the trees, and in order that the carrier may be adapted for the transport of heavy loads I have shown in said figures an additional 65 bracket or brace 11, secured by bolts 12 to the trees. Upon the outer and upper corner of the beam 9 I have shown a track-rail 12^a, which is a half-round strip of iron and adapted to support the wheels 13 of the truck. 70

The preferred form of truck is shown in Figs. 5 and 6 of the drawings and comprises a frame 13^a in the form of a band, which encloses a pair of truck-wheels 13. A hauger 13^b is secured to the outer side of this band 75 and is curved so that its lower end hangs beneath the track-rail, as clearly shown in Fig. 6, and is provided with a swiveling hook 13^c. This arrangement distributes the load between the wheels and prevents their cramping 80 or binding. 14 represents a log supported from such truck, and 15 represents a bucket, which may be employed for the carrying of coal, ore, stone, or the like.

In all cases I prefer to employ instead of 85 the track-rail above mentioned a round track-rail 16, such as shown in the several views of the drawings. This track-rail may be a rod or bar, either flat, round, or angular in cross-section, or it may be a pipe or tube. 90

17, Fig. 7, represents a track-bearer, preferably constructed of wrought iron or steel, and may have its shank passed through the track-beam, as shown in Fig. 3, and fastened with a nut, or it may have a pointed shank, as 95 shown in Figs. 2 and 4. In all cases, however, this track-bearer has its outer end upturned, as clearly shown in Fig. 7, and this upturned end is bifurcated to provide points 17^a, which may after the track-rail is inserted between 100 them be hammered down against such rail, so as to hold it firmly in position and prevent

slipping or drawing of the rail through the bearers.

It has been proposed heretofore to employ a steel cable for a track; but in such case the 5 tension is so great that it is difficult to prevent the cable from slipping through its support. By the employment of a rigid track-rail—such as gas-pipes—the stretching of the track-rail, owing to the weight of the load thereon, is 10 obviated, and the track-rail is maintained at all times at a constant level.

Wherever it is not found convenient to employ trees as a support a special supporting-framework may be constructed—as, for example, 15 as shown in Fig. 3 of the drawings. In this instance the parallel uprights 18 support cross-beams 19, from which depend hangers 20, having upturned ends passed through the track-beam 9 from its lower side; but a better 20 form is illustrated in Figs. 4, 5, and 6 of the drawings, that shown in Fig. 5 consisting of the short upright beam 21, with the diagonally-placed beam 22, having its ground end weighted, and with the track-beam 9 resting 25 directly upon its upper end. The preferred form of construction, however, is shown in Figs. 5 and 6, where, instead of weighting the ground end of the inclined beam, I connect it to a ground timber 23, upon which the lower 30 end of the upright bears. In order to prevent movement of the upright, I provide the stud or pin 24, which is secured in the ground timber with an end of said pin projecting above the face of the ground timber. The 35 upright has an aperture to receive this pin and in this way may be readily removed. Of course the pin may be secured in the post and have an end sharpened to enter the ground timber, or the latter may have an aperture to 40 receive said pin. In this figure I have shown the track-beam supported by a hanger 25, having bolts 26 27 passed through the beam and the upright 21. In this case the bracket 11 is dispensed with. This furnishes a firm and secure 45 foundation for the supporting-framework, and the entire structure, which may be built of rough timbers instead of square timbers shown, is cheap to construct while very strong and efficient for the purposes intended.

50 A carrier of this kind can be very rapidly constructed, and the framework may be made from materials found ready to hand in a forest, and when once constructed there is little liability of its getting out of repair, even in extended use.

I do not claim in this application the form of framework shown in Fig. 4 hereof, as the same is shown and described in my application, Serial No. 396,487, filed June 16, 1891, 60 and is illustrated here to show the application

of my track-bearers to the different forms of frames.

Without limiting myself to the precise details of construction nor arrangement of parts, I claim—

65

1. In an elevated carrier, the combination, with a supporting-frame comprising suitable uprights and a horizontal track-beam supported by said uprights, of a track-rail and bearers therefor, said bearers having their shanks adapted to pass into or through the beam and their outer ends upturned and bifurcated to provide seats for the track-rail and said bifurcations being adapted to be bent to securely embrace the rail, substantially as described.

75

2. In an elevated carrier, the combination, with a supporting-frame comprising suitable uprights and a horizontal track-beam supported by said uprights, of a track-rail comprising a rigid rod or bar and bearers therefor, said bearers having their shanks adapted to pass into or through the beam and their outer ends upturned and bifurcated to provide seats for the track-rail and said bifurcations being adapted to be bent to securely embrace the rail, substantially as described.

85

3. In an elevated carrier, the combination of a supporting-frame comprising suitable uprights and a track-beam secured to said uprights by hangers, having a shank passed through the beam and arms or branches passed into or through the upright, and a track-rail supported by said beam, substantially as described.

95

4. In an elevated carrier, the combination of a supporting-framework comprising a ground timber, an upright having a bearing on said ground timber, a stud or pin engaged with the ground timber and the upright and adapted to prevent lateral movement and permit vertical separation of said upright and timber, an inclined timber having a bearing upon the upright and its lower end secured to the ground timber, and a track-rail supported by the framework, substantially as described.

100

5. In an elevated carrier, the combination of a supporting-frame comprising a ground timber, an upright having a bearing on said timber, an inclined timber having one end secured to said ground timber and its upper end to the upright, and a track-beam secured to the upright and a track-rail carried by said track-beam, substantially as described.

110

ALFRED T. KELLIHER.
